FRAME

Harmon H. Voege, Indianapolis, Ind.

Application June 22, 1949, Serial No. 100,711

3 Claims. (Cl. 160—381)

1

This invention relates to frames and more particularly to screen frames or the like.

The primary object of the invention is to provide a frame made from a molding comprising an elongated outer or front member and an elongated inner or rear member.

Another object of the invention is to provide a frame of the character indicated, the longitudinal marginal portions of the members of which are engaging each other interlockingly to hold the members together.

A further object of the invention is to provide a frame of the character indicated, the abutting end surfaces of the molding pieces of which are mitered to form a rectangular joint and are held in position by flat L-shaped corner members the shanks of which are disposed between the end portions of the front and rear members.

An additional object of the invention is to provide a frame of the character indicated, the corner members of which are secured to the rear members by means of rivets or the like, the front ends of which are covered by the front member.

The invention consists in the details of construction and in the combination and arrangement of the several parts of my improved frames whereby certain advantages are attained, as will be hereinafter more fully set forth.

In order that my invention may be better understood, I will now proceed to describe the same with reference to the accompanying drawings, wherein:

Figure 1 is a view in elevation of a frame constructed in accordance with an embodiment of the invention;

Figure 2 is a sectional view taken substantially on the line 2—2 of Figure 1;

Figure 3 is an exploded view of Figure 2 with parts in section and in perspective;

Figure 4 is a sectional view taken through a front member;

Figure 5 is a transverse sectional view illustrating another embodiment of the invention;

Figure 6 is a transverse sectional view illustrating a further embodiment of the invention; and

Figure 7 is an exploded view of the invention as embodied in Figure 6, the parts being both in section and perspective.

The frame as embodied in Figures 1, 2, 3 and 4 comprises two transverse end pieces 10 of moulding and two longitudinal side pieces 11 of moulding. Each end of each of the pieces 10 and 11 is mitered at an angle of approximately forty-five degrees as at 12, so that the abutting transverse and longitudinal moulding pieces form angles of ninety degrees with each other.

2

Each moulding piece 10 and 11 comprises an outer or front member 13 made from a flat elongated piece of suitable material for instance aluminum or the like, of desired suitable length. 5 One longitudinal marginal portion 14 of each front member 13 is bent at right angles to the main portion of said member, and each main portion is bent longitudinally as at 15 to extend at an obtuse angle in the opposite direction to the marginal portion 14. The direction in which the latter portion extends is called hereinafter forwardly and the marginal portion 14 is the outer edge portion of the member 13. The inner marginal longitudinal portion 16 is bent rearwardly upon itself to form a groove 17.

Each frame moulding piece 10 and 11 comprises also a rear member 18 made from a flat elongated piece of suitable material such as aluminum or the like, and one longitudinal marginal portion 19 of each rear member 18 is bent so that it has an S-shaped cross section and extends forwardly from the main portion of the rear member 18.

The rear member 18 of each moulding piece 10 and 11 is disposed on the rear surface of the corresponding front member 13 so that the edge of the front cross piece of the S-shaped portion 19 enters the groove 17 and the edge of the main portion of the rear member 18 extends outwardly toward the bent marginal portion 14 of the front member 13. The edge of the bent marginal portion 16 of the front member 13 enters the inwardly directed front groove 20 of the S-shaped edge portion 19 of the rear member 18. The marginal portion 14 is bent inwardly as at 21 over the rear face of the main portion of the rear member 18 so that the two members 13 and 18 interlock with each other.

The assembled moulding pieces 10 and 11 are connected with each other to form a frame by means of flat L-shaped corner pieces 22, the shanks 23 of which are inserted in the abutting moulding pieces 10 and 11 so that one of their longitudinal marginal portions is disposed in the rear groove 24 of the S-shaped edge portion of the rear member 18 and the other longitudinal marginal portion is located in the groove 25 formed by the bent portion 14 of the front member 13 and forwardly of the rear member 18.

To facilitate the assembling of the frame each shank 23 of each L-shaped corner piece 22 is provided with a hole 26 and each rear member 18 with a correspondingly arranged hole 27. The rear members 18 are connected with each other by securing the corner pieces 22 to the abutting rear members 18 by means of rivets 28 or the like.

The front members 13 are then arranged on

the corresponding rear members 18 so that the rearwardly bent edge portions 16 are disposed in the front groove 20 of the S-shaped portion of the rear portion. Then the marginal portion 14 of the front member 13 is bent as described above to secure the members 13 and 18 together. The front members 13 cover the rivets 28.

Figure 5 shows a cross section of a slightly modified form of a moulding piece comprising a front member 29 and a rear member 30. The flat front member 29 has a hook shaped inner marginal portion 31 forming a groove 32 and an outer marginal portion 33 bent rearwardly to form a groove 34 extending further rearwardly than the groove 32. The grooves 32 and 34 are facing each other. The rear flat member 30 is formed similar to the rear member 18 and has an inner longitudinal marginal portion 35 with an S-shaped cross section. The outer longitudinal marginal portion of the rear member 30 is bent forwardly upon itself and forms an outwardly opening groove 36. When the mould members 30 and 29 are assembled by inserting the free edge portion of the S-shaped portion 35 into the groove 32 and by locating the free edge portion 37 of the portion 33 of the front member 29 in the groove 36 of the rear member 30. If desired a corner piece 22 can be used for securing abutting molding pieces together.

In Figures 6 and 7 another moulding piece of a slightly modified construction is illustrated. The moulding shown in these figures comprises a front member 38 made from a flat elongated piece of suitable material for instance aluminum, plastic or the like of a desired suitable length. The outer longitudinal marginal portion 39 of each front member 38 is bent rearwardly to extend over the main portion 40 of the member and to form a groove 41. Each main portion 40 is bent to extend forwardly and inwardly at an obtuse angle, as at 42 and then straight inwardly and parallel to the marginal portion 39, as at 43. The inner longitudinal marginal portion of each casing member 43 is bent rearwardly and then inwardly to form a portion 44 having a cross section similar to a rectangular hook, the rear portion 45 of which extends parallel to the portion 43 and is disposed substantially in the same plane as the marginal portion 46.

A rear member 46 has an L-shaped cross section comprising a main portion 47 and an inner marginal portion 48 bent forwardly at a substantially right angle to the main portion 47.

Four of these moulding pieces are assembled and the ends thereof are mitered. Then the moulding pieces are connected to form a frame by means of four flat L-shaped corner members 49. The shanks 50 of these corner members are inserted in the front members 38 so that each shank is disposed between the main portion 40 of the front member 38 and the main portion 47 of the rear member 46 holding each pair of abut-

ting moulding pieces in position. To secure the moulding pieces and the corner members 49 in assembled formation the latter are provided with holes 51 and the rear member 46 with holes 52 arranged so that the holes 51 coincide with the holes 52 when the corner members 49 are inserted in the moulding pieces. Rivets 53 secure the corner pieces 49 and the rear members 46 to each other.

I claim:

1. A frame of the character set forth comprising a plurality of long end abutting units, the units forming corners at their abutting ends, each unit comprising a front piece and a back piece, each front piece having an inturned edge portion along each longitudinal margin forming spaced opposing grooves, each back piece having a double reverse bend along its inner longitudinal margin providing an inwardly directed groove and an outwardly directed groove along said inner margin, the edge of the inturned portion along the inner margin of a front piece being engaged in the inwardly directed groove of the back piece and the groove along the outer margin of the front piece receiving a portion of the outer longitudinal edge of said adjacent back piece, a flat angular coupling plate at each frame corner between the inner and outer pieces, said plate having two shanks each having an inner longitudinal edge within the outwardly directed groove along the inner margin of the adjacent back piece, and means securing said plate to an adjacent back piece.

2. A frame of the character set forth in claim 1, wherein said plate has the outer longitudinal edge of each of its two shanks disposed within the groove along the outer margin of the adjacent front piece between the main body portion of such front piece and the said portion of the outer longitudinal edge of the said adjacent back piece engaged in the same groove.

3. A frame of the character stated in claim 1, wherein the outer marginal portion of each back piece has a double reverse bend providing an outwardly directed groove, one side of which constitutes the said portion of the outer longitudinal edge of said adjacent back piece, the last mentioned outwardly directed groove receiving the adjacent inturned portion of the outer margin of the adjacent front piece.

HARMON H. VOEGE.
